[57] CLAIM

The ornamental design for a rowboat, as shown and described.

DESCRIPTION

FIG. 1 is a top plan view of a rowboat showing our new design;

FIG. 2 is a bottom plan view of FIG. 1;

FIG. 3 is a top perspective view of FIG. 1;

FIG. 4 is a front elevational view of FIG. 1;

FIG. 5 is a left side elevational view of FIG. 1, the right side being a mirror image of that shown;

FIG. 6 is a rear elevational view of FIG. 1;

FIG. 7 is a top plan view of a rowboat showing a second embodiment of our new design;

FIG. 8 is a bottom plan view of FIG. 7;

FIG. 9 is a top perspective view of FIG. 7;

FIG. 10 is a front elevational view of FIG. 7;

FIG. 11 is a left side elevational view of FIG. 7, the right side being a mirror image of that shown; and

FIG. 12 is a rear elevational view of FIG. 7.
